CLAIM

The ornamental design for a light assembly, as shown and described.

DESCRIPTION

FIG. 1 is a front, right and top perspective view of a light assembly, showing my new design.

FIG. 2 is a front, right and top perspective view of a first light of the light assembly in FIG. 1.

FIG. 3 is a rear, left and bottom perspective view of the first light of FIG. 2.

FIG. 4 is a front elevation view of the first light of FIG. 2.

FIG. 5 is a rear elevation view of the first light of FIG. 2.

FIG. 6 is a left side elevation view of the first light of FIG. 2.

FIG. 7 is a right side elevation view of the first light of FIG. 2.

FIG. 8 is a top plan view of the first light of FIG. 2.

FIG. 9 is a bottom plan view of the first light of FIG. 2.

FIG. 10 is an enlarged view of detail 10 in FIG. 1.

FIG. 11 is an enlarged view of detail 11 in FIG. 2.

FIG. 12 is a front, right and top perspective view of a second light of the light assembly in FIG. 1.

FIG. 13 is a rear, left and bottom perspective view of the second light of FIG. 12.

FIG. 14 is a front elevation view of the second light of FIG. 12.

FIG. 15 is a rear elevation view of the second light of FIG. 12.

FIG. 16 is a left side elevation view of the second light of FIG. 12.

FIG. 17 is a right side elevation view of the second light of FIG. 12.

FIG. 18 is a top plan view of the second light of FIG. 12.

FIG. 19 is a bottom plan view of the second light of FIG. 12.

FIG. 20 is an enlarged view of detail 20 in FIG. 12.

FIG. 21 is an enlarged view of detail 21 in FIG. 13.

FIG. 22 is a front, right and top perspective view of a third light of the light assembly in FIG. 1.

FIG. 23 is a rear, left and bottom perspective view of the third light of FIG. 22.

FIG. 24 is a front elevation view of the third light of FIG. 22.

(Continued)

FIG. 25 is a rear elevation view of the third light of FIG. 22. FIG. 26 is a left side elevation view of the third light of FIG. 22.

FIG. 27 is a right side elevation view of the third light of FIG. 22.

FIG. 28 is a top plan view of the third light of FIG. 22.

FIG. 29 is a bottom plan view of the third light of FIG. 22.

FIG. 30 is an enlarged view of detail 30 in FIG. 22.

FIG. 31 is an enlarged view of detail 31 in FIG. 23.

FIG. 32 is a front, right and top perspective view of a forth light of the light assembly in FIG. 1.

FIG. 33 is a rear, left and bottom perspective view of the forth light of FIG. 32.

FIG. 34 is a front elevation view of the forth light of FIG. 32.

FIG. 35 is a rear elevation view of the forth light of FIG. 32.

FIG. 36 is a left side elevation view of the forth light of FIG. 32.

FIG. 37 is a right side elevation view of the forth light of FIG. 32.

FIG. 38 is a top plan view of the forth light of FIG. 32.

FIG. 39 is a bottom plan view of the forth light of FIG. 32.

FIG. 40 is an enlarged view of detail 40 in FIG. 32; and,

FIG. 41 is an enlarged view of detail 41 in FIG. 33.

The broken lines depict portions of the light assembly that form no part of the claimed design. The dot-dash broken lines in FIGS. 2-3, 10-13, 20-23, 30-33, and 40-41 depict the boundaries of the enlargements that form no part of the claimed design.

The light assembly is shown with a symbolic break in its length. The appearance of any portion of the article between the break lines forms no part of the claimed design.

1 Claim, 41 Drawing Sheets
